Pindell, Wright & Pinall ATTORNEYS

UNITED STATES PATENT OFFICE.

FREDERICK W. RIEHL, OF YONKERS, NEW YORK.

DESIGN FOR A RING.

61,329.

Specification for Design.

Patented Aug. 1, 1922.

Application filed November 22, 1921. Serial No. 517,112. Term of patent 3½ years.

To all whom it may concern:

Be it known that I, FREDERICK W. RIEHL, a citizen of the United States, residing at Yonkers, in the county of Westchester and State of New York, have invented a new, original, and ornamental Design for a Ring, of which the following is a specification, reference being had to the accompanying drawing, forming part thereof, wherein—

Figure 1 is a perspective view of a ring illustrating such design;

Figures 2, 3 and 4 are respectively a side elevation, edge view and plan of the same.

I claim:

The ornamental design for a ring as shown.

FREDERICK W. RIEHL.
